UNITED STATES PATENT OFFICE.

CALVIN MARTIN AND MIKE BEASLEY, OF DICKSON, TENNESSEE.

AUTOMATIC RETAINING-VALVE.

No. 918,179.

Specification of Letters Patent.

Patented April 13, 1909.

Application filed September 28, 1907. Serial No. 394,974.

To all whom it may concern:

Be it known that we, CALVIN MARTIN and MIKE BEASLEY, both citizens of the United States, and residents of Dickson, in the 5 county of Dickson and State of Tennessee, have invented a new and Improved Automatic Retaining-Valve, of which the following is a full, clear, and exact description.

The invention relates to fluid pressure 10 brakes of the Westinghouse and like types, and its object is to provide a new and improved automatic retaining valve, arranged to allow of recharging the auxiliary reservoir without releasing the brakes, thus preventing 15 the acceleration of the train, especially when running down a steep grade.

The invention consists of novel features and parts and combinations of the same, which will be more fully described herein- 20 after and then pointed out in the claims.

A practical embodiment of the invention 25 is represented in the accompanying drawings forming a part of this specification, in which similar characters of reference indicate corresponding parts in all the views.

Figure 1 is a sectional elevation of the improvement showing the valve in normal open position when the brakes are released; Fig. 2 is a like view of the same, showing the valve 30 in position when the brakes are set and the auxiliary reservoir is to be recharged, and Fig. 3 is a transverse section of the same on the line 3-3 of Fig. 2.

The casing A of the automatic retaining 35 valve is connected by a pipe B with a pressure retaining reservoir C, and the said casing A is also connected by a pipe D with the train pipe and by a pipe E with the exhaust of the triple valve of usual construction.

40 In the casing A is arranged a cylinder F, into the outer or left-hand end of which opens the pipe D, and in the said cylinder F reciprocates a piston G. The other end of the cylinder F opens into the valve chamber 45 H, provided in its bottom with a valve seat H' for a slide valve I to travel on, and which slide valve has its under side provided with a cavity I' for connecting the pipe E with the exhaust port E' formed in the casing A and leading to the atmosphere. A spring J 50 presses the slide valve I to hold it to its seat H', and the stem I² of the slide valve I is rigidly connected with the piston G, so that when the piston G is shifted the slide valve 55 I moves bodily with the same. Into the

valve chamber H opens the pipe B. The inner end of the cylinder F is provided with a feed groove F', so that when the parts are in the normal open position illustrated in Fig. 1, then the train pipe pressure can pass 60 by way of the pipe D into the outer end of the cylinder F and by way of the feed groove F' and the inner end of the cylinder F to the valve chamber H, from which the train pipe pressure can pass by way of the pipe B into 65 the pressure-retaining reservoir C. Thus the pressure-retaining reservoir C is normally charged with train pipe pressure.

When the parts are in the normal position shown in Fig. 1, then the cavity I' connects 70 the triple valve exhaust to the atmosphere by way of the pipe E, the cavity I' and exhaust port E', the brakes then being released, and when it is desired to set the brakes the engineer reduces the pressure in the train 75 pipe by manipulating the engineer's valve correspondingly and in the usual manner, and when a reduction of air in the train pipe takes place then a like reduction of air takes place in the left hand end of the cylinder F, 80 whereby the preponderance of pressure from the pressure-retaining reservoir C and exerted against the inner face of the piston G, causes the latter to travel in the cylinder F from the right to the left to the position 85 shown in Fig. 2. The movement of the piston G from the right to the left moves the valve I in the same position, so that the triple valve exhaust is cut off from the atmosphere and the pressure in the brake cylinder is re- 90 tained. During the time the retaining valve is held in the closed position, the auxiliary reservoir is recharged to its normal braking pressure by the engineer moving his valve into running position, it being understood 95 that the piston G and the valve I are unaffected while recharging the auxiliary reservoir, as the position of the engineer's valve allows the main reservoir pressure to feed into the train pipe gradually and to force the 100 triple valve to release position, thus recharging the auxiliary reservoir.

In order to release the brakes, the engineer moves his valve into full release position, so 105 that an excess pressure of say thirty or forty pounds, passes from the main reservoir into the train pipe, thus increasing the usual train pipe pressure (70 pounds) to about 20% above that of the pressure-retaining reservoir C. This excess of pressure in the train 110

pipe over that in the pressure-retaining reservoir C, acts on the piston G and forces the same in the cylinder F from the left to the right back into normal position, so that the 5 valve I is also moved back to normal open position, thus connecting the triple valve exhaust with the atmosphere. The air retained in the brake cylinders now escapes to the atmosphere from the triple valve exhaust 10 by way of the pipe E, the cavity I' and the port E', thus releasing the brakes.

From the foregoing it will be seen that the slide valve I is normally open, is closed on setting the brakes, is unaffected on recharging 15 the auxiliary reservoir and is moved to open position on releasing the brakes. By the use of the pressure-retaining reservoir C no waste of air pressure is had. It will also be noticed that the automatic retaining valve 20 has nothing to do with the applying of the brakes, and the engineer can apply the brakes on descending long grades and put the engineer's valve in running position and recharge the train, without releasing the 25 brakes or setting the brakes harder. Thus by the use of this device a train of cars can be run down a steep grade in perfect safety. It will further be noticed that the automatic retaining valve does not allow the brakes to 30 release until the engineer's valve has been moved to full release position, and the valve I has been shifted into open position so as to allow the air pressure to exhaust from the 35 brake cylinder by way of the triple valve exhaust pipe E, cavity I' and port E'. When this takes place the brakes release promptly.

The automatic retaining valve shown and described is very simple, durable in construction, and capable of ready attachment to the 40 fluid pressure brakes as now constructed.

Having thus described our invention, we claim as new and desire to secure by Letters Patent:

1. An automatic retaining valve for fluid pressure brakes, comprising a casing having 45 connection with the train pipe, the triple valve exhaust and the pressure retaining reservoir, a reciprocating piston in the casing, said piston controlling communication between the train pipe and the pressure retaining reservoir and controlled by the pressure from the said train pipe and reservoir, and a slide valve in the casing and moving with the piston, the valve normally opening 50 the triple valve exhaust to the atmosphere and moved into closed position by the piston on setting the brakes.

2. An automatic retaining valve for fluid pressure brakes, comprising a valve chamber having a seat in its bottom through which 60 open two ports, one leading to the atmosphere and with the other of which the triple valve exhaust is connected, the said chamber being connected with a pressure retaining reservoir, a slide valve in the chamber and having a cavity in its under face, a cylinder at one end of the valve chamber and having a feed passage at its inner end, the 65 cylinder being connected with the train pipe, and a piston in the cylinder and secured to 70 the valve.

In testimony whereof we have signed our names to this specification in the presence of two subscribing witnesses.

CALVIN MARTIN.
MIKE BEASLEY.
